FILM REEL

Herman A. de Vry, Chicago, Ill.

Application October 8, 1934, Serial No. 747,393

8 Claims. (Cl. 242—70)

My invention relates to reels or spools particularly for use in motion picture apparatus for winding film.

It is the principal purpose of this invention to provide a reel which cannot readily be distorted or bent out of shape by rough handling.

My invention contemplates the provision of a reel which consists of a hub with two spaced guiding rims connected to the hub by means of 10 spokes in such a fashion that, if the rims are bent apart or pushed together, no tendency to stretch or permanently change the length of the spokes will be produced.

My invention contemplates also the provision 15 of a reel of this character which can be readily knocked down for shipping and assembled in compact form.

My invention also contemplates the provision 20 of a novel means for securing the film to the reel.

The invention further contemplates the provision of a reel construction wherein resilient or spring material may be used to aid the reel in holding its original shape without the necessity 25 of attempting to spot weld the spring material which often results in not only destroying the resiliency but in cracking or breaking the material.

My invention contemplates further the provision 30 of a reel of this character wherein a single spring serves to provide resilient clamping means at several spaced points on the hub for clamping the film to the reel hub.

Other and more specific objects and advantages of the invention will appear as the description proceeds in connection with the accompanying drawings wherein the preferred form of the invention is shown. It is to be understood, however, that the description and drawings are illustrative only and are not to be taken as limiting the invention except in so far as it is limited by the claims.

In the drawings—

Fig. 1 is a side view of the reel;

Fig. 2 is a plan view of the reel;

Fig. 3 is an enlarged plan view of the hub with part of one side thereof broken away to show the interior construction;

Fig. 4 is a sectional view on the line 4—4 of 50 Fig. 3;

Fig. 5 is a sectional view on the line 5—5 of Fig. 3; and

Fig. 6 is a fragmentary detail view illustrating how the film may be attached to the hub by one 55 of the attaching means.

Referring now in detail to the drawings, the reel is made up of a hub 10, a pair of rims 11 and 12, and spokes 13 mounting the rims on the hub. The rims 11 and 12 and the spokes 13 are preferably constructed of flat spring wire having rounded edges such for example as clock spring material. The rims are curved in the plane of greatest width of the wire, and the spokes are secured to the rims for example by means of suitable rivets illustrated at 14. The spokes are fastened to the outer sides of the rims, and the rivets are smoothed off on the inner surfaces of the rims to avoid any sharp edges that might engage the film and tear it. The spokes preferably so connect the hub and the rims as to permit of a limited movement lengthwise of the spokes between the rim and the hub so that, if the rims are bent together or spread apart so as to cause the spokes to bend, the spokes themselves will not be stretched or permanently pulled out of shape.

In order to accomplish this purpose, the hub is made up of the two plates 15 and 16 secured together by means of the posts such as 17 and the screws 18 and 18' for each post. Each of the plates have struck up therefrom the webs such 25 as 19 and 20 for each spoke to pass beneath, and, at the inner end of the spoke, there is provided a suitable stop 21 for each spoke.

From the above description, it will be seen that the spokes may move readily beneath the webs 30 19 and 20 toward and away from the stops 21, the movement thus compensating for any bending of the rims without stretching or permanently distorting the spokes. If the bending is of such an extent as to permanently bend the 35 spokes, the individual spokes may be straightened without causing a dish in the reel because of the sliding mounting of the spokes on the hub.

The means provided for fastening the film to the hub consists of two separate instrumentalities 40 one of which provides a spring grip for gripping the film and the other of which provides teeth for engaging in the perforations in the film. The two instrumentalities are provided by the pieces indicated by the numerals 22 and 23.

The pieces 22 it will be noted are flat strips having the V-shaped portions 24 which extend in between the hub plates 15 and 16 around the posts 17. At opposite ends the members 22 are provided with the portions 25 and 26 which 50 are slightly wider than the space between the hub plates 15 and 16 and which rest on top of these plates between the opposite spokes. These members 22 have the teeth 27 and 28 struck up therefrom, and, between these teeth within the 55

V portion of the members 22, the hub plates have the projections 29 and 30 formed thereon. By an inspection of Fig. 6, it will be seen how the perforations in the film are caused to engage 5 the teeth such as 27 and 28 by merely pressing the film down past the projections 29 and 30 within the V-shaped part of the members 22. The portions 25 and 26 of the members 22 have the proper curvature to fit flat upon the edges of 10 the hub plates 15 and 16.

The members 23 are flat strips bent into substantially T shape as shown in Fig. 3 with the free ends 31 and 32 curved somewhat more than the ends 25 and 26 of the members 22 so that, 15 where they overlap with the ends 25 and 26, a line contact as distinguished from a surface or plane contact is made. This gives a better gripping of the film and always insures that a good grip will be had. The members 23 are pressed 20 outwardly by means of the annular spring 33 which is threaded in suitable slots such as 34 and 35 cut in the doubled portions of the members 23. The free ends of the spring 33 are shown at 36 and 37 in Fig. 3 as turned up on 25 opposite sides of one of the members 23 so that, when any one of these members is pressed inwardly, the spring may adjust itself by relative sliding motion between the ends 36 and 37; and, when the pressure is released, the spring will 30 force the member 23 back into gripping position.

The device may be readily knocked down by removal of the screws 18 and 19 from the several posts 17 so that the rims and the hub plates and the spokes may be stacked flat one on top 35 of the other, and the parts such as the posts and the screws together with the members 22 and 23 may be placed between the spokes to thus form a very compact group for shipping several reels in knocked down condition.

40 From the above description, it is believed that the construction and advantages of this device will be readily apparent to those skilled in this art.

Having thus described one specific form of the 45 invention, what I claim as new and desire to secure by Letters Patent is:

1. A film reel comprising a hub and a pair of rims spaced apart axially of the reel to receive the film therebetween, and spokes mounting the 50 rims on the hub, said spokes being movable endwise with respect to their mounting at one end thereof.

2. A film reel comprising rims of flat spring

wire curved in the plane of their greatest width, a hub, and spokes of spring material connecting the rims to the hub.

3. A film reel comprising rims of spring material, a hub, and spokes connecting the rims to 5 the hub, said spokes being mounted for endwise movement at one end thereof and stop means limiting the endwise movement of said spokes.

4. A film reel having a pair of separable hub plates and having film holding members held 10 between said plates, said film holding members comprising a stationary member held in fixed position between said plates and a radially movable member of different curvature than the stationary member mounted between said plates 15 and separable from said stationary member to receive a film therebetween.

5. A film reel having a pair of separable hub plates and having film holding members held between said plates, said members having end portions overlapping the hub plates, and an intermediate portion extending inwardly between the hub plates, and tie means tying said hub plates together and securing said film holding members between the plates, said members having 25 teeth adjacent the junctions of said portions for receiving the film perforation.

6. A film reel having a pair of separable hub plates and having film holding members held between said plates, said film holding members 30 comprising a stationary member held in fixed position between said plates and a radially movable member of different curvature than the stationary member, said radially movable member overlapping the stationary member and being 35 separable therefrom to receive a film between said members and a spring urging said movable members against the stationary members.

7. A film reel comprising a hub and a pair of rims spaced apart axially of the reel to receive 40 the film therebetween, and spokes mounting the rims on the hub, said spokes being movable endwise in the hub.

8. A reel comprising a hub, a pair of axially spaced rims adapted to receive a film therebetween, spokes connecting the rims to the hub, and said hub having guides for said spokes which restrain said spokes from movement axially or circumferentially of the hub but allow endwise movement of the spokes on the hub, and stop 50 means limiting the endwise movement of said spokes.
